(57) **CLAIM**

The ornamental design for a single cell assembly for a plant-growing tray as shown and described.

DESCRIPTION

FIG. 1 is a front, left and top perspective view of a single cell assembly for a plant-growing tray shown in a disassembled state, showing my new design.

FIG. 2 is a rear, right and bottom perspective view thereof shown in a disassembled state.

FIG. 3 is a front elevation view thereof shown in a disassembled state.

FIG. 4 is a rear elevation view thereof shown in a disassembled state.

FIG. 5 is a left side elevation view thereof shown in a disassembled state.

FIG. 6 is a right side elevation view thereof shown in a disassembled state.

FIG. 7 is a top plan view thereof shown in a disassembled state.

FIG. 8 is a bottom plan view thereof shown in a disassembled state.

FIG. 9 is a front, right and top perspective view of FIG. 1 shown in an assembled state.

FIG. 10 is a rear, left and bottom perspective view thereof shown in an assembled state.

FIG. 11 is another front, right and top perspective view of the single cell assembly for a plant-growing tray shown in an assembled state with environmental subject matter; and, FIG. 12 is another rear, left and bottom perspective view of the single cell assembly for a plant-growing tray shown in an assembled state with environmental subject matter.

(Continued)

The broken line showing of a plant-growing tray and single cell assemblies in FIGS. 11-12 is for the purpose of illustrating environmental subject matter and forms no part of the claimed design.
